US0D1032520S

(12) **United States Design Patent** (10) **Patent No.:** **US D1,032,520 S**
(45) **Date of Patent:** **** Jun. 25, 2024**

(54) **TWIN PORT ADAPTER**

(71) **Applicant:** **ALCOR SCIENTIFIC LLC**,
Smithfield, RI (US)

(72) **Inventor:** **Peter J. Sacchetti**, North Falmouth,
MA (US)

(73) **Assignee:** **ALCOR SCIENTIFIC LLC**

(**) **Term:** **15 Years**

(21) **Appl. No.:** **29/876,908**

(22) **Filed:** **May 30, 2023**

(57) **CLAIM**

The ornamental design for a twin port adapter, as shown and described.

DESCRIPTION

FIG. 1 is a top perspective view of a twin port adapter, with an arm thereof in an open position;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top perspective view thereof, with the arm thereof in a closed position;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a top right perspective view thereof, with the arm thereof in the closed position shown in environmental use; and,

FIG. 16 is a top left perspective view thereof, with the arm thereof in the closed position shown in environmental use. The broken lines shown depict environmental subject matter and form no part of the claimed design.

1 Claim, 15 Drawing Sheets
